UNITED STATES PATENT OFFICE.

WHITMAN RUSSELL, OF GREENFIELD, MASSACHUSETTS.

INTERNAL-COMBUSTION ENGINE.

1,072,777.

Specification of Letters Patent. Patented Sept. 9, 1913.

Application filed December 14, 1911. Serial No. 685,672.

To all whom it may concern:

Be it known that I, WHITMAN RUSSELL, a citizen of the United States, residing at Greenfield, in the county of Franklin and State of Massachusetts, have invented certain new and useful Improvements in Internal-Combustion Engines; and I do hereby declare the following to be a full, clear, and exact description of the invention, such as will enable others skilled in the art to which it appertains to make and use the same.

My invention relates to improvements in internal combustion engines, and it consists in the constructions, combinations and arrangements herein described and claimed.

An object of my invention is to provide an improved valve gear adapted to operate efficiently with an elimination of wasteful leakage without the employment of troublesome packings.

A further object of my invention is to provide a simple and durable cylindrical valve gear, which will be efficiently protected from the deteriorating and distorting effects of the heat of combustion, thereby insuring a uniform and efficient operation under all practical conditions.

In the accompanying drawings, forming a part of this application, and in which similar reference symbols indicate corresponding parts in the several views:—Figure 1 is a vertical, axial section, illustrating one embodiment of my invention; Fig. 2 is a section on the line 2—2 of Fig. 1; and, Fig. 3 is a section on the line 3—3 of Fig. 1.

Referring to the drawings, 1 indicates the water-cooled cylinder of an internal combustion engine mounted on a closed crank casing 2, and provided with the usual piston 3, connecting rod 4, crank 5, and engine shaft 6. A cylinder head 7 is provided with an axially-extending flange 8 spaced from the periphery of the water-cooled cylinder 1 and closely engaging an annular shoulder 9 on the latter to provide a closed annular chamber about the outer wall of said cylinder, registering circumferential admission ports 10 and exhaust ports 11 extending through said flange and cylinder. The head 7 is firmly clamped against the end of the cylinder by a series of bolts extending axially

through said head and the cylinder wall, as shown in the drawings. A cylindrical valve 12 is rotatably mounted within such chamber on the outer wall of the water-cooled cylinder 1, and provided with a single port 13 for controlling the admission port 10 and exhaust port 11; said cylindrical valve being provided with an annular gear face 14 meshing with a gear 15 on a counter-shaft 16. A drive shaft 17 is shown actuatingly connected to the engine shaft 6 and counter-shaft 16, respectively, by intermeshing spiral or skew gears 18 and bevel gears 19, said drive and counter-shafts being journaled in a hollow casing 20 which incloses the gears 15 and 19, and is secured to the flange 8.

I have illustrated my invention applied to a four-cycle engine, in which the valve 12 is driven at one half the rotative speed of the engine shaft 16, Fig. 3 showing the position of the valve at the beginning of the power stroke.

The drawings show my invention and all operating parts, and omit all illustration of the usual igniting devices, and pipe connections. The cylindrical valve 12 is rotated through 90° during each stroke of the engine piston 3, and the operation will be understood without further description thereof.

From the above description, it will be clear that my invention provides an improved construction adapted to eliminate all wasteful leakage without the necessity of employing troublesome packings, and in which the valve is protected from the deteriorating and distorting effects of the heat of combustion; thereby providing a durable construction adapted for efficient and certain operation under all practical conditions.

My invention is adapted for advantageous application to multi-cylinder engines by extending the counter-shaft 16 and securing at suitable positions thereon duplicate gears 15 for driving the cylindrical valves of the several cylinders.

I have illustrated and described preferred and satisfactory constructions, but changes could be made within the spirit and scope of my invention.

I claim:—

In an internal combustion engine, the combination of a water-cooled cylinder having

an exterior annular shoulder provided with a cylindrical peripheral wall, a cylindrical head having a cylindrical flange adapted to fit slidably over said peripheral wall to provide a closed annular chamber about said water-cooled cylinder, means for clamping said head firmly against the end of said cylinder, and a cylindrical valve within such

chamber rotatably mounted on the outer wall of said water-cooled cylinder.

In testimony whereof, I affix my signature, in presence of two witnesses.

WHITMAN RUSSELL.
